BRACKET FOR VENETIAN BLINDS

Paul J. Harris, Portland, Oreg., assignor to Rite-Hite Corporation, Portland, Oreg.

Application August 1, 1949, Serial No. 107,953

2 Claims. (Cl. 248—264)

1

This invention relates generally to window blinds and particularly to a bracket for Venetian blinds.

The main object of this invention is to produce a bracket for Venetian blinds which will be easy to manufacture, rugged in construction and easy to install and operate.

The second object is to make a bracket which will make possible an accurate adjustment of the top rail in order to provide a desired clearance between the lower rail and the window sill.

Attention is drawn to my U. S. Patent 2,332,851, over which this is an improvement.

I accomplish these and other objects in the manner set forth in the following specifications as illustrated in the accompanying drawing, in which:

Fig. 1 is a perspective view of the bracket in a closed or rail supporting position and showing the blind in dotted lines.

Fig. 2 is a perspective view of the bracket showing the apron supporting arm swung out to unlock the adjusting mechanism. Like numbers of reference refer to the same or similar parts throughout the several views:

Referring in detail to the drawing, there is shown a flat plate 10 having a lug 11 formed along one edge, normal to the plane of the plate 10. The plate 10 and lug 11 have a number of screw holes 12 and 13 formed therein for attaching the bracket to a frame or casing.

Projecting from the plate 10 are the upturned hooks 14 which are punched out of the metal in the plate 10.

Against the plate 10 is mounted an angle plate 15 having a plurality of openings 16 formed therein, two or more of which can receive hooks 14 at the same time and effectively position the top leg 17, upon which can rest the top plate 18 of a Venetian blind which, if desired, may be fastened to the leg 17 by screws passing through the holes 19 in the legs 17.

From the plate 18 hangs the cords 20 which support the lowermost rail (not shown). A bracket 21 tiltably supports the top rail 22 which in turn supports the tapes 23, on whose cross ties 24 are supported the blind slats in a conventional manner.

The problem solved by this invention is the accurate adjustment of the elevation of the plate 18 in order to provide the desired clearance above the window sill.

It is a well-known fact that mounting Venetian blinds is ordinarily a difficult task, owing to the fact that the blind may vary slightly in length before and after cleaning or under extreme atmospheric conditions.

In my prior patent referred to I employ a screw

2

adjustment which, although providing a fine adjustment, was slow in action and rather expensive to produce.

In the present invention, I have provided a vertical channel 26 having adapted to receive an apron 27 between its front edge 28 and lugs 29. An ear 30 projects from the channel 26 and is attached by a rivet 31 to the plate 10.

In the middle of the channel 26 is disposed a toothed ear 32 capable of engaging the edge of the leg 17 between two teeth 33 as shown in Fig. 1. A downturned ear 34 holds the ear 32 against the plate 10 and a pair of center punches 35 and 36 latch the ear 32 in a closed position.

It can be seen that in order to adjust the length of a blind and therefore its clearance above a window sill, it is only necessary to swing the apron 27 outwardly, thereby releasing the plate 15 and making it possible to raise or lower it at will. Thus it can be seen that the elevation of the bottom rail can be accurately fixed.

I claim:

1. A bracket for Venetian blinds consisting of a flat plate adapted to be secured to an upright support, said plate having a lug at one side thereof of normal thereto, an angle plate movably mounted against said flat plate, said plates having a series of hooks and openings registering with each other whereby said angle plate may be held at a pre-determined elevation, an apron supporting channel having its lower end hinged to the lower end of said flat plate and having a plurality of notches formed in the side thereof adapted to engage said angle plate and fix its position when said apron is in a vertical position.

2. In a bracket for Venetian blinds, the combination of a flat plate having hooks projecting from a flat side thereof, an angle plate having a series of openings registering with said hooks adapted to support said angle plate in a selected vertical position, a channel member having a closed end hinged to one corner of said plate and foldable along one edge of said plate, said channel having a projecting ear provided with slots adapted to receive said angle plate and means for holding said channel ear against said flat plate.

PAUL J. HARRIS.
